APPARATUS FOR BENDING GLASS SHEETS

Lewis Jex-Blake Forbes, Rainhill, and George William Terence Bird, Prescot, England, assignors to Societe Anonyme des Manufactures des Glaces et Products Chimiques de Saint-Gobain, Chauny & Cirey, Paris, France, a corporation of France

Application January 23, 1939, Serial No. 252,464
In Great Britain January 29, 1938

1 Claim. (Cl. 49—67)

This invention relates to apparatus for bending glass sheets.

It is customary to bend glass sheets by making a wooden former and bending the glass over it, the sheet or plate having been previously heated to the softening point or allowed to retain its residual heat of formation. The wooden former is either of solid wood or consists of a plurality of spaced battens fixed to a base or to side members. When a single sheet or only a few sheets have to be bent to a given curvature, the cost of making the former unduly increases the cost of the bent sheets. When a large number of sheets have to be bent, the former gradually loses its correct form by reason of the wood charring away more rapidly at those parts which first come into contact with the glass.

According to the invention, a former is formed of a plurality of slats or elements held side by side in a frame, with guiding means on the frame adapted to permit the elements to slide relatively one to another back and forth in one direction, so that their front edges, or front surfaces, present substantially a curved surface and means for holding the elements against relative movement when pressed against the glass. The elements may be held against relative movement either by compressing the plurality of elements to lock them by friction or by pressing them against the glass by means of a templet or former pressed against their back edges. These elements may be either slats or reglets (i. e. bars of small cross section), according to the desired shape which is to be given to the surface of the glass sheet treated.

The slats may be used for the realization of surfaces which can be generated by straight generating lines. When skew surfaces, spherical surfaces for example, must be realized with a former according to the invention, one will have to make use of slats or reglets.

Said elements may be made of any appropriate material and preferably wood.

The invention also comprises means for pressing together two formers, having elements of which the front edges lie on surfaces curved similarly but inversely, while the glass sheet is between them, the pressing means preferably consisting of two frames adapted to slide horizontally in guides and fluid pressure means adapted to press them towards one another while the formers and the glass sheet are interposed.

In the accompanying drawings:

Figure 1 is a plan view and

Figure 2 an enlarged side view looking toward

the left end of Figure 1 and represents one form of realization of a bending former according to the invention.

Figure 3 is a perspective view on a smaller scale of a device for giving the former correct shape,

Figure 4 is a perspective view of a former for cooperating with the opposite side of a sheet of glass when the glass is bent by the device of Figure 1.

10 Figure 5 is a part side view on a smaller scale of a bending apparatus with the formers shown in Figures 1, 2 and 4 in place,

Figure 6 is a central vertical section on the line 6—6 of Figure 8,

15 Figure 7 is a vertical section on the line 7—7 of Figure 9,

Figure 8 is a plan view, reduced in size, of Figure 6.

Figure 9 is an enlarged plan view of Figure 7.

20 Figure 10 is a plan view showing the combined use of the formers shown in Figures 1 and 4.

Referring to Figures 1 and 2, the former consists of a plurality of wooden slats 1, held between two uprights 2 and 2a. Each slat 1 has two slots 3, through which pass two bolts 4, which pass also through holes in the uprights 2 and 2a. When the nuts 10 of the bolts 4 are slack, the slats are free to slide between the uprights 2 and 2a, being guided by the bolts 4 in the slots 3.

25 As shown in Figure 1, the slats 1 are so placed between the uprights 2 and 2a as to present a front (the lower part in Figure 1) which is substantially a cylindrical surface. The templet consisting of one or more templet parts 5, shown 30 in Figure 3 serves to give the front a surface of any desired curvature. Two templet parts 5, having their upper edges 6 curved to the desired curvature, are mounted on a base 7 by brackets 8, and end pieces 9 are similarly mounted thereon.

35 The former of Figure 1 is placed on the templet so that the front edges of the uprights 2 and 2a rest on the end pieces 9, and, with the nuts 10 slack, the slats 1 are shaken or tapped down until all the slats rest on the edges 6 of the two templet parts 5. The bolts 10 are then tightened so

40 that the slats 1 are compressed between the uprights 2 and 2a, and are then held against sliding by friction. The former then is substantially equivalent to a former of solid wood having a front surface of the desired curvature. The curvature can be changed by replacing the templet parts 5 by other templets and again shaping the former on them. Further, if the curvature becomes altered by reason of the central slats 45 charring away more rapidly than the outer slats,

50

the former can be given the correct shape again by the use of the laminar former. This can be accomplished by slackening the nuts 10 and shaking or taping down the slats 1 until the operative faces of the slats rest on the edges 6 of the template parts 5 as above explained.

It has been discovered that a sheet can be bent more accurately to a given curvature if the convex former has a solid or nearly solid surface, but that the concave former can consist of spaced battens without affecting the accuracy of the bend. Thus the convex former of Figure 1 can be used with the concave former of Figure 4. It is satisfactory, however, to make up the convex and concave formers both from a plurality of slats in the manner shown in Figure 1.

Figure 5 shows the bending apparatus, in which two face-plates 14 are shown carrying a former as in Figure 1 on the right, and a former as in Figure 4 on the left. In this arrangement the glass sheet depends from a plurality of gripping tongs A connected to freely swing from chains B. This construction permits the sheet or plate of glass to bend freely under the influence of the formers without any resistance from the supporting means, thereby eliminating any tendency toward distortion of the sheet during the bending operation and after the completion thereof. The formers are hung on the face-plates 14 by hooks 16 engaging the upper edges of the face-plates. The apparatus for pressing the two face-plates towards one another is shown on the right only, that on the left being similar. The face-plate 14 is on a frame 16 comprising a box girder 17, having four guiding surfaces 18. These run between eight rollers 19 (two on each surface 18) carried on the side members 20 of the fixed frame 21. Thereby the face-plate 14 is able to slide forward and backward (to the left or right respectively as seen in Figure 5). A hydraulic cylinder 22 is fixed by bolts 23 between the side members 20, the box girder 17 having an aperture shown by the dotted lines 24 to permit the girder to move to the left over the cylinder 22. The ram 25 of the cylinder 22 is fixed to the face-plate 14. Pipes 26 provided with valves 26a are connected to an accumulator (not shown) and supply fluid to the two ends of the cylinder 22.

In operation, with the parts in the position shown in Figure 5, the heated glass sheet, which may be suspended by tongs or otherwise supported, is brought between the two formers, and fluid is supplied to the back ends of the cylinders 22 to force the face-plates 14 and formers carried by them together, pressing and bending the glass sheet between them.

Figure 6 shows an alternative form of former, hung on a face-plate 14. A plurality of wooden

slats 1, all of the same width from back to front, are held in a box frame, having upper and lower members 27, so that they are free to slide therein, being guided between the members 27 and the uprights 2. A former, consisting of two templets 28 attached to the face-plate 14 by brackets 29, is adapted to engage the back edges of the slats 1.

In operation, the slats 1 are pressed back against the templets 28, so that the front surface 10 of the former has the curvature of the templets, and, when the glass is pressed between the formers, the pressure is applied to the glass by the templets 28 and through the slats. In this former when the curvature becomes altered by reason of charring, all the slats of the plurality are again brought to the same length, for instance, by passing them through a thickness planer.

Figure 7 shows a former in which a plurality of reglets 30 are held in a frame consisting of the movable sides 31, 32, 33, 34.

The sides 31 and 32 have slots 35-36 through which pass the bolts 37-38 which pass also through holes 39-40 in the sides 33-34. In the sides 31, 32 are also holes 41-42 through which 25 pass the bolts 43-44.

When the reglets 30 are placed horizontally as shown in the front view 7, the desired curvature is given to the front presented by these reglets by pressing against their outer surfaces 30 a reversely curved templet in a manner similar to that which the slats of the former of Figure 1 are brought to the desired curvature in conjunction with the templet shown in Figure 3.

The nuts 45-46 of the bolts 43-44 are then 35 tightened so as to compress the reglets between the sides 31-32. The nuts 47-48 of the bolts 37-38 are in their turn tightened so that the reglets are also compressed between the sides 33-34.

40 The reglets thus being held against relative movement by friction, the former shown on this Figure 7 is then brought to the desired position for the bending of glass sheets.

Having described our invention, we declare that 45 what we claim and desire to secure by Letters Patent is:

In apparatus for bending glass sheets, a former including a frame, a plurality of elements held 50 side by side in said frame, adjustable holding means associated with the frame to hold the elements in any of a plurality of selected positions, and a template having a predetermined contour carried by the frame and in engagement with the rear edges of the elements for positioning the 55 front edges of the elements to give the front surfaces thereof the curvature of said template.

LEWIS JEX-BLAKE FORBES.
